DRIVING MECHANISM FOR CHURNS

Albert C. Hougland, St. Paul, Minn., assignor to
 Crane Company of Minnesota, St. Paul, Minn.,
 a corporation of Minnesota

Application August 17, 1931, Serial No. 557,597
 In Canada October 9, 1930

5 Claims. (Cl. 74—389)

It is my object to provide for churning a novel arrangement of driving and controlling mechanism, together with a compact, protective housing, adapted to prolong the life of the machine. 5 Other objects are: to promote smooth operation and facility in operating the several churn elements; to guard against damage to the mechanism by improper operation and to generally improve the construction and arrangement of the 10 controls.

The invention will be best understood by reference to the accompanying drawings in which Figure 1 is an end view of a churn with my improved drive; Fig. 2 is a vertical section through the drive taken on the line 2—2 of Fig. 4 and with a portion of the gear housing removed; Fig. 3 is a vertical section taken longitudinally through the main drive shaft and gear housing; Fig. 4 is a horizontal section through the axis 15 of the churn and drive and with the gear housing cover removed; Fig. 5 is a vertical section taken on the line 5—5 of Fig. 3; Fig. 6 is a transverse section through the several shafts taken on the line 6—6 of Fig. 4 and Fig. 7 is a fragmentary, side view showing the openings in the gear housing for the horizontal control levers.

In the drawings, the numeral 8 indicates a large churn of the common type which is revolvable about a horizontal axis and supported in large bearings at its end. A large spider 9 is secured to one end of the churn body and has radially extending arms to which are fixed a tubular shaft 10 (Fig. 4) extending coaxially with the churn. This shaft 10 is journaled in a 20 suitable trunnion 11 supported on a gear housing 12. A large spur gear 13 is fixed on the shaft 10 for turning the churn body and extending axially through the shaft 10 is a second shaft 14 for driving butter working rolls 15 within the churn body. These rolls are journaled in a head or end 25 wall 16 of the churn and are adapted to be driven by intermeshing spur gears 17 embraced within the spider 9. One of the gears 17 is located centrally on the end of the churn and is fixed on the shaft 14 to drive the other gears 17.

Normally revolvable on the shaft 14 is a sprocket wheel 18 having a toothed face adapted to be engaged by a sliding clutch member 19. This clutch member is keyed to the shaft 14 and is movable by a hand lever 20 to make driving connection between the sprocket wheel 18 and shaft 14. A chain 21 for driving the sprocket wheel 18 is driven by a sprocket wheel 22 fixed on a horizontal shaft 23. A spur gear 24 is also 30 fixed on the shaft 23 and is arranged to con-

tinuously mesh with a pinion 25 keyed to a main drive shaft 26 (Fig. 3). As best shown in Figs. 3 and 5, a shaft 27 is mounted in continuation of the shaft 26 in the housing 12 and is supported at one end in a recess in the pinion 25, 5 said pinion having an offset hub 28 which is keyed to the shaft 26. Slidable longitudinally on the shaft 27, but keyed thereto, is a gear 29 having a hub portion 30 recessed to receive the pinion 25 and to establish driving connection 10 therewith. A hub portion of the gear 29 is formed with a peripheral recess to receive diametrically opposite projections on a fork member 31 for shifting the gear 29 longitudinally on the shaft 27. The gear 29 may be moved to 15 three distinct positions in one of which it is in engagement with the pinion 25. In another position of the gear 29 it is in mesh with a gear 32 on the shaft 23 (Fig. 6), and the third position of the gear 29 is an idle or neutral one. 20 To transmit rotary motion to the large gear 13, a gear 33 is fixed on the shaft 27 and gears 34 and 35 are fixed on a shaft 36. The gear 33 meshes with the gear 34 and the gear 35 with the gear 13. 25

The several shafts 23, 27, and 36 have suitable bearings in the end walls of the gear housing 12 and said housing has a large removable cap 12a to allow access to the gears, shafts and bearings therein. As shown in Fig. 7, the cap 30 12a has an opening 37 through which the hand lever 20 projects and another opening 38 for a gear shift lever 39. As shown in Fig. 5, the lever 39 is secured to the upper end of a vertical shaft 40 in the housing 12 and the fork 31 is fixed on 35 said shaft. A notched quadrant 41 is secured to the outer surface of the housing 12 to be engaged by a detent 42 movably secured to the lower surface of the lever 39. This detent 42 is spring pressed toward the quadrant 41 and has 40 a handle 43 adapted to be manipulated to withdraw it from the quadrant. A rigid finger 44 (Figs. 4 and 5) projects from the lever 39 to engage the lever 20. The finger 44 engages a surface 45 on the lever 20 when the latter is in 45 position to render the drive shaft 14 for the butter working rolls inoperative. A stop shoulder 46 on the lever 20 is struck by the finger 44 when the lever 20 is in position to render the butter working rolls operative. 50

The shaft 26 projects from the gear housing 12 and has a suitable bearing support 47 for its outer extremity. Freely revolvable on the shaft 26 is a pulley 48 adapted to be driven by a suitable motor driven belt. A clutch element 49 of 55

the well known conical type is provided to engage the inner periphery of the pulley 48 and is secured by keys 50 to the shaft 26, said element being slidably longitudinally on the shaft. The element 49 is normally held in driving engagement with the pulley 48 by spring pressed bolts 51. Coiled springs on the bolts 51 engage a disk 52 and end thrust exerted by said springs, through the bolts 51, is transmitted by the disk 52 to the ends of the keys 50.

A collar 53 is freely revoluble in a suitable recess in the clutch element 49 and studs 54 project from a fork member 55 to engage the collar 53 for shifting the clutch element 49. The fork member 55 is pivotally supported on a bracket 56 secured to the housing 12 and an end of said fork member carries a roller 57 operatively engaging an arcuate cam 58. This cam is secured to the lower extremity of a clutch lever 59 having a pivot 60 projecting from the gear housing 12. A toothed quadrant 61 is provided to engage a suitable dog on the lever 59 for retaining the lever in predetermined positions. A button 62 on the lever 59 is adapted to be actuated to release the lever from the quadrant 61.

Adjacent to the clutch element 49 is rigidly mounted a brake ring 63 adapted to be engaged by an annular surface 64 on said clutch element. The ring 63 is integral with a cylindrical housing 65 bolted to the gear housing 12.

30 Operation

In operation, the pulley 48 may be continuously driven by connection with a suitable motor (not shown) and the master clutch, including the element 49 and connections with the lever 59, is employed to render the churn operative or inoperative at will. When the lever 59 is moved to the left from the position shown in Fig. 2, the cam 58 actuates the fork member 55 to withdraw the clutch element 49 from driving engagement with the pulley 48. Continued movement of the lever 59 to the left brings the annular surface 64 of the clutch element 49 into engagement with the stationary brake ring 63, to thereby stop or prevent rotation of the main drive shaft 26. I thus make it possible to quickly and easily stop rotation of the large churn body 8 in any desired position for filling, emptying or other purpose. By combining the brake with the clutch, I guard 50 against placing undue strain on the mechanism, as in case an attempt is made to drive the churn with the brake in operative position. During the filling of the churn, the clutch element 49 may be maintained in contact with the brake ring 63 and the lever 39 moved to either operative position so that the churn body is held in the desired position. The first operation of the machine for butter making is that of churning and for this operation the churn body is 55 rotated at the higher speed, the lever 39 being moved to its position shown in Fig. 4, and the master clutch element 49 moved to engage the pulley 48. When the lever 39 is moved to that position, the fork 31 is actuated to slide the gear 29 to the right, into direct driving engagement with the pinion 25. The drive is now established directly from the shaft 26 to the shaft 27, thence through the gears 33, 34, 35 and 13, shafts 36 and 10, and spider 9 to the churn body 8. During the 60 churning at the high speed, I prevent positive driving of the butter working rolls in order to prevent undue strain on the mechanism. To this end, the finger 44 engages the surface 65 on the lever 20 and prevents movement of said lever in such direction as to cause the clutch member 19 to engage

the teeth on the sprocket 18. If an attempt is made to move the lever 39 to the high speed position when the lever 20 is in position to operatively connect the butter working rolls with the power drive, the finger 44 merely strikes stop shoulder 46 on the lever 20. Thus movement of the lever 39 to the high speed position is impossible until the lever 20 has been moved to render the drive for the butter working rolls inoperative.

When the churning operation is complete, the lever 39 may be moved to its neutral position, in which the gear 29 is retained out of engagement with the pinion 25 and gear 32. With the lever 39 in the neutral position and shaft 26 in operation, the shaft 23, chain 21 and sprocket wheel 18 15 merely idle until the lever 20 is actuated to connect the sprocket wheel 18 with the shaft 14. To drive the rolls 15 the lever 20 is moved to render the shaft 14 operative and for working the butter the lever 39 is then moved from its central, neutral 20 position to the right, as seen in Fig. 4. This moves the gear 29 into mesh with the gear 32 on the shaft 23 so that the slow speed drive is established from pinion 25 to gear 24, to shaft 23, gears 32 and 29, shaft 27, gears 33, 34, 35, and 13, to the churn 25 body. Simultaneously the butter working rolls 15 are rotated through the connections with the shaft 14 hereinbefore described. If, as is sometimes desirable, the butter working rolls are to be operated while retaining the churn body stationary, it is 30 only necessary to move the lever 39 to its neutral position and to place the lever 20 in position to connect the sprocket wheel 18 with the shaft 14.

What I do claim as my invention and desire to secure by Letters Patent is:

1. Driving mechanism for a churn having a revoluble body and butter working rolls therein comprising, a gear housing, a shaft in said housing, a second shaft projecting from said housing in axial alignment with said first mentioned shaft, means for driving said first mentioned shaft directly from said second shaft, a sliding gear on said first mentioned shaft, a pinion on said second shaft, a gear train in said housing including a second gear on said first mentioned shaft for rotating said churn body, a counter shaft in said housing, a gear on said counter-shaft in mesh with said pinion, a second gear on said countershaft arranged to mesh with said sliding gear, a third gear on said countershaft 45 operatively connected to said butter working rolls and power-driven means for rotating said second shaft.

2. Driving mechanism for a churn having a revoluble body and butter working rolls therein comprising, a gear housing, a shaft in said housing, a second shaft projecting from said housing in axial alignment with said first mentioned shaft, a sliding gear on said first mentioned shaft, a pinion on said second shaft, means formed on said sliding gear and pinion for driving said first-mentioned shaft directly from said second shaft, a gear train in said housing including a second gear on said first mentioned shaft for rotating said churn body, a counter-shaft in said housing, a gear on said counter-shaft in mesh with said pinion, a second gear on said countershaft arranged to mesh with said sliding gear, a third gear on said countershaft 55 operatively connected to said butter working rolls and power-driven means for rotating said second shaft.

3. Driving mechanism for a churn having a revoluble body and butter working elements comprising, a shaft for driving said butter work-

ing elements, a second shaft operatively connected to said body for rotating the same, change speed gearing for driving said second shaft at relatively high and low speeds, a manually operable element for changing speeds, a second manually operable element for rendering said first mentioned shaft operative and means operatively connected to said change speed element for preventing the movement of said second manually operable element to operative position when said churn body is driven at the relatively high speed. 5
10
15
20

4. Driving mechanism for a churn having a revoluble body and butter working elements comprising, a shaft for driving said butter working elements, a second shaft operatively connected to said body for rotating the same, change speed gearing for driving said second shaft at relatively high and low speeds, a manually operable lever for changing speeds, a second manually operable lever for rendering said first mentioned shaft operative, said levers being mounted in

proximity to each other, and interengaging members associated with said levers for preventing the driving of said butter working elements when said churn body is driven at the relatively high speed.

5. Driving mechanism for a churn having a revoluble body and butter working elements comprising, a shaft for driving said butter working elements, a second shaft operatively connected to said body for rotating the same, change speed 10 gearing for driving said second shaft at relatively high and low speeds, a manually operable element for changing speeds, a second manually operable element for rendering said first mentioned shaft operative and means for preventing the driving 15 of said butter working elements when said churn body is driven at the relatively high speed and for preventing the driving of said churn body at the relatively high speed when said first mentioned shaft is operative.

ALBERT C. HOUGLAND. 20
